PERMANENT WAVING DEVICE

Daniel Lakenbach, Norwich, Conn.

Application February 2, 1939, Serial No. 254,217

16 Claims. (Cl. 132—36.2)

The invention relates to devices used in the art of imparting a wave or curls to human hair, which art is commonly referred to as permanent waving. More particularly, the invention relates to a sachet or similar device employed in that branch of the art in which the permanent waving is accomplished without the use of electricity, heating elements, and cumbersome associated apparatus.

10 In the art of permanent waving, without the use of electricity, the heat necessary for imparting the wave or curls to the human hair is obtained by a device, generally a pad, which comprises an envelope attached to a backing of aluminum foil, the envelope containing a mixture of certain chemicals and being provided with a plurality of perforations, a strip of flannel or felt being saturated with a solution or "lotion" and then placed over the surface of the envelope so that the moisture from the flannel or felt strip may seep through the perforations and come into contact with the chemical mixture, resulting in an exothermic reaction between the chemicals and solution and in the development of an amount 15 of heat and a degree of temperature sufficient to impart a permanent wave to the hair which has been curled upon a rod and enveloped by the pad.

20 The amount of heat thus developed is usually of a degree of temperature, slightly above the boiling point of water, which temperature is maintained during the course of the chemical reaction for approximately five minutes.

25 A disadvantage of the prior art appliance constituting the sachet resides in the fact that it necessitates the use of at least three different types and concentration of solution. Ordinary human hair may be generally classified, with respect to its texture and therefore the amount and degree of heat required to impart a permanent wave thereto, into three types, namely one 30 of a coarse texture, a medium texture and a fine texture. In addition to these three specific types, the amount and degree of heat necessarily applied thereto is likewise governed by the condition of the hair with respect to prior treatments given thereto, for instance, bleaching. A further difficulty arises by reason of the fact that certain 35 types of hair, in order to give a pleasing appearance, or to suit the particular complexion of the patron, must have imparted thereto a particular type of wave which may be broadly classified as loose or tight, or small or large. It is only by long 40 experience and a systematic course of education by the manufacturers of the permanent waving devices that the average hairdresser is able to de-

termine not only the amount of steaming time necessary, but the strength of the solution which is to be applied to the hair to secure the amount and degree of heat which will give the best results. The practice in accordance with the prior art has been to supply the hairdresser with three different strengths of solution, the hairdresser being advised to use a particular solution for a particular type of hair. The strength of solution determines the amount and degree of the heat developed by the exothermic reaction, which amount and degree of heat, however, are always approximately the same. As even the provision of these three specific strengths of solution is at best an attempt at providing an average strength of solution for the different types of hair, absolutely proper results are generally secured only by accident.

45 In accordance with my invention, I provide a permanent waving device, constituting a sachet, which eliminates the manifold disadvantages of the devices of the prior art.

50 In its broadest aspect, my invention comprises a permanent waving sachet constituted of a specially constructed paper envelope containing the powdered chemicals which are to enter into chemical reaction with the solution to be applied thereto, to produce the amount and degree of heat necessary for creating a permanent wave which is most suitable to the particular texture of hair and the type of wave desired. The primary object of my invention is to provide a permanent waving sachet which will produce, as desired, a plurality of different amounts and degrees of heat secured by the use of a single lotion or solution of a particular strength or concentration. A further object of the invention is to provide a construction of sachet and a composition of the ingredients designed to enter into the exothermic reaction, which will retain the proper and exact amount of moisture inside the sachet, while at the same time prevent steam from escaping from the pad in any amount which might cause burns, the chemical reaction in the sachet, by reason of the presence of a particular ingredient, being such that the steam is produced gradually and uniformly.

55 A further object of my invention is to provide a permanent waving sachet of a construction which enables the operator to replenish the supply of solution to the chemical ingredients within the sachet from time to time in an amount sufficient to regenerate the exothermic reaction so as to bring the heat, falling as the chemical reaction takes place, again to its maximum point.

and to maintain such maximum point and therefore the amount and degree of heat for a further steaming period. A specific feature of my novel permanent waving sachet resides in the provision 5 of means enabling the operator to supply such additional amount of solution to the pad and to supply it in such a manner as to be most effective in raising the temperature to the desired degree, irrespective of the particular position of the pad 10 upon the head, for instance, whether the pad and associated appurtenances, such as the protector and curling rod, is upon the top of the head, the side of the head, or near the nape of the neck, in each of which positions it lies at a different 15 angle to the vertical.

Further objects of my invention will be evident to those skilled in the art. For instance, the chemical-containing envelope of my sachet is so constructed that the powdered chemicals can- 20 not sift out. In accordance with my invention also, I provide a novel type of spring clip which, when applied to the curling rod upon which the tress of hair has been wound, will rest upon the surface of the protector, the resiliency of the 25 spring clamp being sufficient to hold the sachet tightly around the curling rod so as to eliminate the possibility of any steam escaping.

A particular embodiment of my invention is illustrated in the accompanying drawing, in which 30 Fig. 1 is a plan view of a conventional type of curling rod, with a tress of hair wound thereon, in position upon the surface of a clamping device or protector, with a tightening handle inserted into the end of the curling rod to effect a tightening 35 of the hair wound thereon; Fig. 2 is a plan view of the device of Fig. 1, with the exception of the tightening handle, with my novel permanent waving sachet and spring clamp applied thereto; Fig. 3 is a front view of the devices showing the application of a replenishing supply of 40 solution to the envelope, through an aperture in the backing sheet of the sachet; Figs. 4 and 5 are plan and sectional views, respectively, of the pad; and Fig. 6 is a perspective view of the spring clip 45 constructed in accordance with my invention.

Referring more particularly to the drawing, in which similar reference characters identify similar parts in the several views, 10 and 11 designate the two clamping elements of the conventional protector, which are pivotally connected by link 12. The curling rod 13, conventional in construction, having a gripping clip 14, is secured upon the upstanding flanges 15 and 16 of the protector in well known fashion, the curling rod being rotatable by the tightening handle and rod 55 17. Beneath the protector is a felt pad 18, of conventional form and function.

The elements just described form no part of my present invention, and are, therefore, not described in greater detail.

60 My novel permanent waving sachet is constituted of an envelope 19 made of a paper which is water-absorbent and yet as strong, if not stronger, when wet than when it is dry. Such paper is available on the market in the familiar form used for paper toweling. The envelope is formed with two end flaps 20 and 21 and contains the mixture of ingredients which is to enter into the exothermic reaction with the "lotion", the 65 envelope being adhesively secured on a gummed sheet of paper or aluminum foil 22 of a length approximating the length of the protector and of a width sufficient to completely embrace the curling rod 13 and the tress of hair 23 wound thereon, 70 with the two longitudinal edge portions of the

sheet or strip lying along the edges of the protector when the sachet is placed in position, as shown in Figs. 2 and 3.

The envelope for application to the particular elements shown in the drawing is approximately 5 2½ inches long and 1½ inches wide, the paper or aluminum foil backing 22 being 2½ inches long and 2 inches wide, leaving the free longitudinal edges of approximately ¼ of an inch in width on either side of the envelope secured thereto. 10

Approximately centrally of the gummed paper or aluminum foil 22, I provide an aperture 24 of approximately diamond shape. The size of the aperture in the particular embodiment illustrated in the drawing is approximately 1 inch length- 15 wise from apex to apex, and ¾ of an inch cross-wise from apex to apex. The aperture, however, may be of a size approximately ⅓ by ⅓ of an inch.

The permanent waving sachet as thus consti- 20 tuted, and in which is contained a mixture of the ingredients 25, is first dipped into a solution for a few seconds until the envelope becomes well saturated, no squeezing thereof, to remove excess moisture, being necessary, and is applied to the 25 tress of hair wound upon the curling rod by curving the same along its longitudinal center line, with the diamond-shaped aperture extending upwardly, as shown in Fig. 3. The width of the sachet is such that the two longitudinal edges 30 thereof, when applied to the curler, rest upon the protector. The spring clip 26 is then applied to the sachet so as to have the end loops 27 and 28 thereof straddle the sachet, the longitudinal portions of the spring clip being effective to firmly 35 hold the sachet in close contact with the curling rod and the protector.

In accordance with my invention, and by using 40 a permanent waving sachet as hereinabove described, I am enabled to control and obtain different amounts and degrees of heat, developed by the exothermic reaction, such different heats, with respect to amount and temperature, being as many in number as three or four, all by using the same strength and concentration of solution. 45

The procedure for accomplishing these results is as follows:

The sachet is first dipped entirely into the solution for a few seconds, sufficient to completely 50 saturate it. The sachet is then applied to the wound tress of hair as hereinabove described, when the heat will be found to come very gradually up to approximately 104° C., which temperature it will hold for exactly six minutes. At the expiration of such six-minute period, when the heat commences to decline, there are added a few drops of the solution, for instance by an ordinary eye-dropper, such as illustrated in dotted lines in Fig. 3, the drops of solution being applied to the body of the envelope exposed by the aperture 24 55 in the backing sheet. The effect of these few drops of solution is to bring the degree of heat again up to approximately 104° C. for three minutes. After the expiration of such additional three-minute period, there may again be applied 60 a few drops of the solution to the exposed surface of the envelope, the heat rising again to the proper steaming temperature for approximately three more minutes.

For example: To impart a loose wave or curls 70 to a coarse head of hair, it is not necessary to add any solution by means of the eye-dropper, so that the proper amount of heat is maintained for exactly six minutes at slightly above the boiling point, such steaming time being the proper heat 75

for the particular texture of hair and type of wave. For a medium quality of hair, the same procedure is followed, but after the first six minutes of steaming, there should be applied five or 5 six drops of solution to the exposed surface of the envelope, bringing the heat produced by the exothermic reaction up to slightly above the boiling point for an additional three minutes. The necessary heating time of nine minutes for the 10 particular texture of hair is thus attained. For a very fine texture of hair, the procedure is repeated with an additional three-minute steaming period obtained by the addition of five or six drops of solution to obtain the steaming period 15 of twelve minutes at slightly above the boiling point, which is necessary for this type of hair texture.

An important feature of my construction of 20 sachet is the form of the aperture 24. In the illustrated embodiment of my invention, I have shown such aperture as of a diamond shape. It will be understood by those skilled in the art that in imparting a permanent wave to a complete head of hair, the protectors and curling rods take 25 different positions upon the head, some being positioned upon the crown of the head, some along the areas adjacent the crown, and some in the areas immediately above the nape of the neck. These various positions of the protector and curling rod present different angularities of the surface of the sachet to the vertical. If then, the 30 additional drops of solution, in accordance with my invention, are to be applied to the area of the envelope exposed by the aperture, the drops of 35 solution should be applied at such points within the exposed area where it will most easily penetrate and be absorbed by the envelope. Thus, when the sachet is upon the crown of the head, the drops of solution should be applied at approximately 40 the center of the exposed area of the envelope. If, however, the sachet is at an angle, for instance when applied to an area removed from the crown of the head, the drops should preferably be applied a little to one side of the 45 center of the exposed area so that such drops will be readily absorbed by the envelope material.

By forming the aperture 24 in substantially diamond shape, the operator is enabled to apply the drops of solution either at the center of the 50 exposed area or at any apex thereof so as to secure the rapid absorption of the solution and preclude the possibility of the drops of solution rolling off the curved sachet before they have had a chance to be absorbed by the paper material. Obviously, while I have illustrated and 55 described the aperture as of substantially diamond shape, any similar shape would give substantially equally good results. For instance, even a circular aperture could be used if the operator is careful to apply the drops of solution 60 at the proper point near the periphery of the circular aperture, i. e. at a point which is substantially the highest in the particular position of the protector and curling rod upon the head.

Coming now to another feature of my invention, the prior art methods of using a so-called chemical pad necessitated the use of an extra piece of flannel or absorbent paper with the 65 sachet so that the solution and the mixture of chemicals contained in them do not enter into their chemical reaction so suddenly as to produce a sudden and violent steaming. The function of such extra piece of flannel or absorbent 70 paper has been to absorb the moisture from the

solution and to gradually give it up to the mixture of chemicals so as to produce a gradually progressing chemical reaction.

In accordance with my invention, I provide for the retention of the proper and exact amount 5 of moisture inside of the pad or sachet rather than, as has been done by the prior art, by means of a piece of flannel or absorbent paper outside of the pad. In accordance with this feature of my invention, I add to the powdered 10 chemicals contained within the envelope approximately 10% by weight of wood flour. This amount of wood flour is effective to absorb the moisture from the solution and will produce a 15 chemical reaction which automatically and uniformly progresses as the wood flour releases the moisture into the powdered mixture of chemicals in which it is incorporated. The wood flour also functions as a means of preventing any great amount of steam escaping at one time and will 20 thus eliminate the danger of burns due to a violent chemical reaction, the wood flour permitting the development of the steam gradually and uniformly.

While I have described a specific embodiment 25 of my invention, obviously various changes therein, particularly in the size, configuration and respective disposition of the various elements thereof may be made without departing from my invention. Likewise, while I have specified wood flour as the particular ingredient which will act as a reservoir for the moisture within the pad and for releasing such moisture gradually and uniformly to the mixture of chemicals 30 with which it is incorporated, I desire to include 35 within the scope of the appended claims the chemical equivalents now known for such material, so long as they have the characteristics and properties making them suitable for the purpose 40 of effecting the same result.

I claim:

1. A sachet for permanent waving without the use of electricity, comprising an envelope of soft, pliable, absorbent material containing a mixture 45 of chemicals adapted to enter into exothermic reaction with a solution, a backing sheet for said envelope having an aperture approximately in the center of the backing sheet and through which drops of permanent waving solution may be applied to the surface of the envelope exposed 50 through such aperture.

2. A sachet for permanent waving without the use of electricity, comprising an envelope of soft, pliable, absorbent material containing a mixture 55 of chemicals adapted to enter into exothermic reaction with a solution, a backing sheet for said envelope having an aperture of substantially diamond shape positioned approximately in the center of the backing sheet and through which drops of permanent waving solution may be applied to the surface of the envelope exposed 60 through such aperture.

3. A sachet for permanent waving without the use of electricity, comprising an envelope of 65 soft, pliable, absorbent material containing a mixture of chemicals adapted to enter into exothermic reaction with a solution, a backing sheet for said envelope of substantially the same length as the envelope but of greater width so as to 70 provide two longitudinally extending edge areas on each side of the envelope, said backing sheet having an aperture approximately in the center of the backing sheet and through which drops of permanent waving solution may be applied to 75

the surface of the envelope exposed through such aperture.

4. A sachet for permanent waving without the use of electricity, comprising an envelope of soft, pliable absorbent material containing a mixture of chemicals adapted to enter into exothermic reaction with a solution, a backing sheet for said envelope of substantially the same length as the envelope but of greater width so as to provide 10 two longitudinally extending edge areas on each side of the envelope, said backing sheet having an aperture of substantially diamond shape positioned approximately in the center of the backing sheet and through which drops of permanent 15 waving solution may be applied to the surface of the envelope exposed through such aperture.
5. A sachet for permanent waving as claimed in claim 1, in which the aperture of the backing sheet is of a configuration permitting the application of drops of solution to the surface of the envelope exposed by the aperture in such manner 20 as to have such solution absorbed by the pad irrespective of the position of the pad upon the head.
6. A sachet for permanent waving as claimed in claim 4, in which the aperture of the backing sheet is of a configuration permitting the application of drops of solution to the surface of the envelope exposed by the aperture in such manner 25 30 as to have such solution absorbed by the pad irrespective of the position of the pad upon the head.

7. A sachet for permanent waving without the use of electricity, comprising an envelope formed 35 of a soft, pliable, absorbent material having two closure flaps, a backing sheet of gummed paper wider than the width of said envelope and having said envelope adhesively secured thereto, said backing sheet being provided with an aperture approximately at the center of the pad.
8. A sachet for permanent waving without the use of electricity, comprising an envelope formed 40 of a soft, pliable, absorbent material having two closure flaps, each provided with an adhesive, a 45 backing sheet wider than the width of said envelope and having said envelope adhesively secured thereto, said backing sheet being provided with an aperture approximately at the center of the pad.

9. A sachet for permanent waving without the use of electricity, comprising an envelope formed 50 of a soft, pliable, absorbent material having two closure flaps, a backing sheet wider than the width of said envelope and having said envelope adhesively secured thereto, said backing sheet being provided with a substantially diamond-shaped aperture approximately at the center of the pad.

10. A device for permanent waving hair by the exothermic reaction of chemicals, comprising 55 in combination a protector clamp, a curling rod adapted to have a tress of hair wound thereon, a sachet comprising an envelope of soft, pliable, absorbent material containing a mixture of chemicals adapted to enter into exothermic reaction with a solution, a backing sheet for said envelope having an aperture positioned approximately in the center of the backing sheet, and means for 60 securing said sachet in curved position about the curling rod so as to have the edges of the backing sheet in close contact with the protector clamp, said means permitting the application through said aperture in the backing sheet, to the envelope, of drops of permanent waving solution 65

periodically as the exothermic reaction in the envelope progresses.

11. A device for permanent waving hair by the exothermic reaction of chemicals, comprising in combination a protector clamp, a curling rod 5 adapted to have a tress of hair wound thereon, a sachet comprising an envelope of soft, pliable, absorbent material containing a mixture of chemicals adapted to enter into exothermic reaction with a solution, a backing sheet for said envelope having an aperture of substantially diamond shape positioned approximately in the center of the backing sheet, and means for securing 10 said sachet in curved position about the curling rod so as to have the edges of the backing sheet 15 in close contact with the protector clamp, said means permitting the application through said aperture in the backing sheet, to the envelope, of drops of permanent waving solution periodically 20 as the exothermic reaction in the envelope progresses.

12. A device for permanent waving hair by the exothermic reaction of chemicals, comprising in combination a protector clamp, a curling rod 25 adapted to have a tress of hair wound thereon, a sachet comprising an envelope of soft, pliable, absorbent material containing a mixture of chemicals adapted to enter into exothermic reaction with a solution, a backing sheet for said envelope of substantially the same length as the envelope 30 but of greater width so as to provide two longitudinally extending edge areas on each side of the envelope, said backing sheet having an aperture of substantially diamond shape positioned approximately in the center of the backing sheet, 35 and means for securing said sachet in curved position about the curling rod so as to have the edges of the backing sheet in close contact with the protector clamp, said means permitting the application through said aperture in the backing sheet, to the envelope, of drops of permanent waving solution periodically 40 as the exothermic reaction in the envelope progresses.

13. A sachet for permanent waving without the use of electricity comprising an envelope of a 45 soft, pliable material containing a mixture of chemicals adapted to enter into exothermic reaction with a solution and approximately 10% by weight of wood flour.

14. A sachet for permanent waving without 50 the use of electricity, comprising an envelope of a soft, pliable material containing a mixture of chemicals adapted to enter into exothermic reaction with a solution and approximately 10% by weight of a material which will absorb a quantity of permanent waving solution and release the same gradually and uniformly to the chemical mixture, for the gradual and uniform development of an exothermic reaction between such chemical mixture and the permanent waving 55 solution.

15. A sachet for permanent waving without the use of electricity, comprising an envelope of a soft, pliable material containing a mixture of chemicals adapted to enter into exothermic reaction with a solution and approximately 10% by weight of a material which will absorb a quantity of moisture applied to the envelope and release the same gradually and uniformly to the chemical mixture for the gradual and uniform 60 development of an exothermic reaction of the chemicals contained in the envelope.

16. A device for permanent waving hair by the exothermic reaction of chemicals, comprising in combination a protector clamp, a curling rod 75

adapted to have a tress of hair wound thereon, a sachet comprising an envelope of soft, pliable absorbent material containing a mixture of chemicals adapted to enter into exothermic reaction with a solution and approximately 10% by weight of such chemicals, of wood flour, a backing sheet for said envelope having an aperture approximately in the center of the backing sheet, and means for securing said sachet in

curved position about the curling rod so as to have the edges of the backing sheet in close contact with the protector clamp, said means permitting the application through said aperture in the backing sheet, to the envelope, of drops of permanent waving solution periodically as the exothermic reaction in the envelope progresses. 5

DANIEL LAKENBACH.
